US0D1050993S

(12) **United States Design Patent** (10) Patent No.: **US D1,050,993 S**
(45) Date of Patent: ** Nov. 12, 2024

(54) **VEHICLE OUTSIDE MIRROR**

(71) Applicant: **GM GLOBAL TECHNOLOGY OPERATIONS LLC**, Detroit, MI (US)

(72) Inventors: **Dongwan Jo**, Incheon (KR);
Myeongseon Choi, Incheon (KR);
Zooyoung Oh, Incheon (KR)

(73) Assignee: **GM GLOBAL TECHNOLOGY OPERATIONS LLC**, Detroit, MI (US)

(**) Term: **15 Years**

(21) Appl. No.: **29/892,000**

(22) Filed: **May 12, 2023**

(51) LOC (14) Cl. **12-16**

(52) U.S. Cl.

USPC **D12/187**

(58) **Field of Classification Search**

Primary Examiner — Katrina A Betton

(57) **CLAIM**

The ornamental design for a vehicle outside mirror, as shown and described.

DESCRIPTION

FIG. 1 is a front and left side perspective view of a vehicle outside mirror showing our new design; the mirror image of the vehicle outside mirror is claimed, but not shown;

FIG. 2 is a front elevation view of the vehicle outside mirror of FIG. 1;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle outside mirror that form no part of the claimed design.

1 Claim, 7 Drawing Sheets
